A. F. WARNOCK

TABLE

Filed April 6, 1926

Patented Oct. 30, 1928.

1,689,652

UNITED STATES PATENT OFFICE.

ANDREW F. WARNOCK, OF PORTLAND, OREGON, ASSIGNOR OF ONE-THIRD TO THOMAS TESDAL, OF PORTLAND, OREGON.

TABLE.

Application filed April 6, 1926. Serial No. 100,084.

My invention relates to extension type of tables, the object being to provide means whereby the extension leaf may be stored within the table as an integral unit without hinging or folding the same, and whereby it is caused to assume its proper place as a part of the table top by the extending of the table.

I accomplish this object by means of the construction illustrated in the accompanying drawing, which is a part of this application for Letters Patent, like characters of reference indicating like parts throughout the several views thereof, and in which:

Fig. 1 is a transverse section of the table top in closed position.

Fig. 2 is a similar view with the table top partially open.

Fig. 3 is a similar view with the table top further opened.

Fig. 4 is a similar view with the table top fully opened, and the extension leaf in position.

Fig. 5 is a longitudinal section of the table top with the extension leaf in stored position therein.

Fig. 6 is a section upon line 6—6 of Fig. 5.

Fig. 7 is an end elevation of the table top with the extension leaf in stored position.

The table top is of the ordinary construction, having separable top members 8 and 9 with aprons 10. At each end of the table are a pair of coacting guide slides, the outer of each pair of slides, 11, being secured to the top member 8, and the inner slide of each pair, 12, being secured to the top member 9. These slide guides operate in a guide member 13, as shown in Fig. 5, and the guide members 13 are connected by a cross piece 14 to which the legs 15 are secured. By this construction I eliminate all top supporting members and slides from the central portion of the table.

The upper surface of each of the guides 11 and 12 is notched to receive the extension leaf 16, which lies in said notches beneath the table top when it is not in use. When the leaf 16 is in stored position one end of the notch in the guide slides 11 contacts with the leaf, as shown at 11^a in Fig. 1, while the opposite end of said notch is upwardly inclined from a point 11^b spaced some distance from the leaf 16. That end of the notch in slide 12 adjacent the inclined portion just described contacts with the leaf 16 as at 12^a in Fig. 1, and the opposite end of the notch

is spaced some distance from the leaf, as shown at 12^b.

As the top members 8 and 9 are separated the ends 12^b and 11^b of the notches contact with the leaf 16, and said leaf begins to ride upon the inclined portion of the notch in slide 11, as shown in Fig. 2. Continued movement of the top members 8 and 9 apart causes the leaf 16 to ride completely up the inclined portion of the notch in slide 11 into the position shown in Fig. 3.

When the leaf is in the position shown in Fig. 3 it is necessary to raise it out of the notches in the slides 11 and 12 into position such that the top members 8 and 9 may be closed upon the leaf. This I accomplish by providing a shaft 17 journaled in the slide members 12 and having cams 18 secured thereupon adapted to lift the leaf into its uppermost position, as shown in Fig. 4. To operate said shaft and cams I provide an arm 19 secured to the shaft, and a rod 20 passing from said arm through one of the aprons 10 and terminating in a suitable handle 21. When not in use the cams 18 lie beneath the stored leaf as shown in Figs. 1, 2, 3 and 5. When it is desired to raise the leaf into its uppermost position a pull upon the handle 21 rotates the shaft 17 and the cams 18 into the position shown in Fig. 4, and thus raises the leaf from the position shown in Fig. 3 into the position shown in Fig. 4, in which latter position it is ready to have the top members 8 and 9 closed upon it.

With this construction of table it is necessary that the top members 8 and 9 should move equally from the center of the table as they are separated. This may be accomplished in many ways, that found convenient in materializing my invention is a right and left hand threaded screw 22 mounted in a bearing 23 secured to the cross piece 14, and held longitudinally therein by collars 24, as shown in Fig. 6. Secured to the top members 8 and 9 are threaded brackets 25 and 26 adapted to receive said threaded screw, and the screw extends through one of the aprons 10 to terminate in a handle 27 for operating the same, as shown in Fig. 6.

My invention may be made of any size and constructed of any materials deemed convenient and suitable for a device of this character, and while I have illustrated and described a form of construction found desirable in materializing my invention, I wish

to include in this application all mechanical equivalents and substitutes that may fairly be considered to come within the scope and purview of my invention as defined in the appended claim.

Having disclosed my invention so that others may be enabled to construct and to use the same, what I claim as new, and desire to secure by Letters Patent is:—

10. In a table: movable top members; an extension leaf positioned beneath said top members to guide the same in their relative movement as the table is extended when not in

use; coacting slides for said members; coacting notches in said slides to receive said leaf and adapted to raise the leaf when said slides are operated; a shaft journaled in said slides; a cam upon said shaft adapted to position the raised leaf intermediate said top members; a lever upon said shaft; and a rod connected to said lever for operating said shaft.

In witness whereof I claim the foregoing as my own I hereunto affix my signature at Portland, county of Multnomah, State of Oregon, this 1st day of April 1926.

ANDREW F. WARNOCK.
